(57) **CLAIM**

The ornamental design for control element for a speaker housing, as shown and described.

DESCRIPTION

FIG. 1 is a perspective view of a control element for a speaker housing showing my new design;

FIG. 2 is a reduced top plan view thereof;

FIG. 3 is a front elevational view thereof;

FIG. 4 is a side elevational view thereof, the opposite side elevational view being a mirror image thereof; and,

FIG. 5 is a back elevational view thereof.

The broken line showing of the speaker housing in FIGS. 1-5 is for illustrative purposes only and forms no part of the claimed design.
